BOOT SOLE

Guillaume Sacre, Goodhue, Minn., assignor to Red Wing
Shoe Company, Inc., Red Wing, Minn.

Filed Feb. 13, 1974, Ser. No. 442,207

Term of patent 14 years

Int. Cl. D2—04

U.S. Cl. D2—320

FIG. 1 is a bottom plan view of a shoe sole showing my new design, the side opposite thereto being plain;

FIG. 2 is a side elevational view thereof;

FIG. 3 is an elevational view of the other side;

FIG. 4 is a front elevational view;

FIG. 5 is a rear elevational view;

FIG. 6 is an enlarged cross sectional view taken on the line 6—6 of FIG. 1; and

FIG. 7 is an enlarged cross sectional view taken on the line 7—7 of FIG. 1.

I claim:

The ornamental design for a boot sole, substantially as shown and described.
